UNITED STATES PATENT OFFICE.

ROBERT L. McELROY, OF NEW YORK, N. Y.

MUFFLER.

1,242,219.

Specification of Letters Patent.

Patented Oct. 9, 1917.

Application filed December 23, 1915. Serial No. 68,327.

To all whom it may concern:

Be it known that I, ROBERT L. McELROY, a citizen of the United States, residing in New York, in the county of New York and State of New York, have invented certain new and useful Improvements in Mufflers, of which the following is a specification.

The objects of this invention are primarily to provide, a muffler of a light, simple and cheap form of construction, which may be used for muffling the exhaust from pressure engines of all kinds, but which is more especially adapted to be used on those of the explosion type; and by its peculiar construction, contours, and the arrangement of the entire structure, the gases in their passage therethrough are divided into a plurality of currents which impinge upon each other, whereby while the noise of the exhaust is greatly lessened, back-pressure is reduced to a minimum.

These and other features, capabilities and advantages will more fully appear from the subjoined detail description of one specific embodiment thereof, in which—

Figure 1 is a fragmentary view of the present invention, partly in section.

Fig. 2 is a side view thereof, partly in section.

Fig. 3 is a section taken on the line 3—3, of Fig. 1.

Fig. 4 is another section taken on the line 4—4, of Fig. 1.

Fig. 5 is a plan diagram showing the direction of the gases.

Fig. 6 is another plan diagram showing the path of gases from exhaust to the atmosphere.

Fig. 7 is a plan view of the muffler complete.

Fig. 8 is a fragmental side elevation of the fan-shaped mouth of the muffler.

In Fig. 1 there is shown an exhaust pipe connection 1 leading from the engine to the muffler chamber passing in the direction of the arrow *a*. The housing is comprised of an annular tubular member 2 which is jointed at its axes by a similarly constructed tubular member 3, the said member 3 being, in the present instance, arranged in a plane

substantially at right angles to the plane in which member 2 is disposed in such a manner that they are connected to one another to produce an arrangement resembling two connected chain links.

The first expansion chamber 2, which is of substantially tubular construction, is intersected by a cut 4 through its tubular sectional area which may be ascertained in Figs. 1 and 4. The second expansion chamber 3 is so arranged as to inclose this slotted exhaust opening 4 so that when the gases from the engine follow the direction of the arrows *a*, *b* and *c*, they come together at the point or slot 4 and the mutual impinging of the gases at equal pressure cause the same to escape through the slot 4 whereupon the gases are permitted to flow into the second chamber 3, and thence they follow in the direction of the arrow *d* to the atmosphere. It will therefore be seen that my device comprises essentially two substantially hollow annular members in communication with one another, one member communicating with the connection from the engine, and the other annular member communicating with the connection to the atmosphere.

The tubular member 3, as clearly shown in Figs. 1 and 7, conforms to the inner periphery of the tubular member 2 while passing therethrough, which is comparatively small relatively to the enlarged portion 6 thereof disposed at the outer periphery of the tubular member 2. The fan-shaped pipe connection 5 from which the exhaust gases are fed to the atmosphere, is connected to the enlarged portion 6, being comparatively large where it connects with the enlarged portion 6 and being formed into a spread-out narrow fan-shaped mouth 7 at its free end.

In order to more fully understand the action of the gases in my construction, reference may be had to Figs. 5 and 6, wherein Fig. 5 represents the direction of gases as they leave pipe 1 at expansion chamber 2 and impinge upon each other at the point 4 and thereafter discharge to the atmosphere at 5. Fig. 6 may be termed a side elevation of Fig. 5 inasmuch as it represents the path 100

- of the gases as they impinge at the slot 4 and are expanded outwardly into the second expanding chamber 3 through the narrow orifice formed by the slot 4.
- 5 While any suitable means may be provided for affixing the muffler in operative position to a vehicle or other satisfactory support, I have shown in the drawings, Fig. 1, a pair of lugs X, Y, which may be drilled 10 and tapped in order to permit of the use of suitable bolts for the purpose described.
- Heretofore in mufflers of the known type, such as used in pleasure vehicles and the like, the excess exhaust pressure from gas 15 engines and the like, has been progressively cooled and expanded through a series of chambers having a common port, one leading into the other, and thence to the atmosphere.
- 20 In the present device, I do away with all baffle-walls and simply cause the gases to travel in such a direction that the stream is divided into two arms or branches, said two branches then being consequently directed 25 fully against each other, thereby constituting an elastic and gradual expanding means, the said gases being limited in their expansion to atmosphere by reason of the constriction of the orifice 4. This orifice, as 30 shown, is preferably annular, but it is obvious that it may be of any other shape or contour that will permit the simultaneous meeting of equal volumes of gas. It is therefore apparent that by doing away with 35 the customary baffles, and also the numerous chambers common to prior mufflers, the present modification may be made in a cast metal such as aluminum, thereby lightening the muffler and making the same a unitary 40 or integral structure.
- I claim:
1. A muffler comprising a housing forming a primary annular chamber and a secondary annular chamber, the principal planes of said chambers intersecting each other, each chamber passing through the center of and surrounding a portion of the other chamber, said chambers being connected by an annular opening disposed in 45 that portion of the primary chamber that is surrounded by the secondary chamber, said chambers being provided respectively with lateral openings remote from said annular opening.
  - 50 2. A muffler comprising a housing forming a primary annular chamber of constant internal diameter, and a secondary annular chamber, the principal planes of said chambers intersecting each other, each chamber passing through the center of and surrounding a portion of the other chamber, said chambers being connected by an annular opening disposed in 55 that portion of the primary chamber that is surrounded by the secondary chamber, said chambers being provided respectively with lateral openings remote from said annular opening.
  - 60 3. A muffler comprising a housing forming a primary annular chamber and a secondary annular chamber, the principal planes of said chambers intersecting each other at right angles, each chamber passing through the center of and surrounding a portion of the other chamber, said chambers being connected by an annular opening disposed in 65 that portion of the primary chamber that is surrounded by the secondary chamber, said chambers being provided respectively with lateral openings remote from said annular opening.
  - 70 4. A muffler comprising a housing forming a primary annular chamber and a secondary annular chamber, the principal planes of said chambers intersecting each other, each chamber passing through the center of and surrounding a portion of the other chamber, said chambers being connected by an annular opening disposed in 75 that portion of the primary chamber that is surrounded by the secondary chamber, said chambers being provided respectively with lateral openings remote from said annular opening.
  - 80 5. A muffler comprising a housing forming a primary annular chamber and a secondary annular chamber, the principal planes of said chambers intersecting each other, each chamber passing through the center of and surrounding a portion of the other chamber, said chambers being connected by an annular opening disposed in 85 that portion of the primary chamber that is surrounded by the secondary chamber and in the plane of the secondary chamber, said chambers being provided respectively with lateral openings remote from said annular opening.
  - 90 6. A muffler comprising a housing forming a primary annular chamber and a secondary annular chamber, the principal planes of said chambers intersecting each other, each chamber passing through the center of and surrounding a portion of the other chamber, said chambers being connected by an annular opening disposed in 95 that portion of the primary chamber that is surrounded by the secondary chamber, said chambers being provided respectively with lateral openings remote from said annular opening.
  - 100 7. In a muffler, the combination of a housing forming a primary annular chamber and a secondary annular chamber, the principal planes of said chambers intersecting each other, each chamber passing through the center of and surrounding a portion of the other chamber, said chambers being connected by an annular opening disposed in 105 that portion of the primary chamber that is surrounded by the secondary chamber, said chambers being provided respectively with lateral openings remote from said annular opening, the secondary chamber gradually decreasing in internal diameter from its lateral opening to the opposite side of the chamber.
  - 110 8. In a muffler, the combination of a housing forming a primary annular chamber and a secondary annular chamber, the principal planes of said chambers intersecting each other, each chamber passing through the center of and surrounding a portion of the other chamber, said chambers being connected by an annular opening disposed in 115 that portion of the primary chamber that is surrounded by the secondary chamber, said chambers being provided respectively with lateral openings remote from said annular opening, and pipes in said lateral openings co-axial with the line of intersection of said planes.
  - 120 9. In a muffler, the combination of a housing forming a primary annular chamber and a secondary annular chamber, the principal planes of said chambers intersecting each other at right angles, each chamber passing through the center of and surrounding a portion of the other chamber, said chambers being connected by an annular opening disposed in 125 that portion of the primary chamber that is surrounded by the secondary chamber, said chambers being provided respectively with lateral openings remote from said annular opening.

cipal planes of said chambers intersecting each other, each chamber passing through the center of and surrounding a portion of the other chambers, said chambers being connected by an annular opening disposed in that portion of the primary chamber that is surrounded by the secondary chamber, said chambers being provided respectively with lateral openings remote from said an-

nular opening, and a fan shaped pipe connection communicating with said lateral opening of the secondary chamber and having its principal plane coincident with the plane of the secondary chamber. ¹⁰
